UNITED STATES PATENT OFFICE.

S. STUART WILLIAMSON, OF BRIDGEPORT, CONNECTICUT, ASSIGNOR TO A. F. CARMAN, OF BROOKLYN, NEW YORK, AND S. D. WILLIAMSON, OF WASHINGTON, DISTRICT OF COLUMBIA.

CAR-TRUCK.

SPECIFICATION forming part of Letters Patent No. 286,565, dated October 9, 1883.

Application filed July 27, 1883. (No model.)

To all whom it may concern:

Be it known that I, S. STUART WILLIAMSON, a citizen of the United States, residing at Bridgeport, in the county of Fairfield and State of Connecticut, have invented certain new and useful Improvements in Car-Journals; and I do hereby declare the following to be a full, clear, and exact description of the invention, such as will enable others skilled in the art to which it appertains to make and use the same.

My invention relates to certain new and useful improvements in car-journals, and has for its object to provide an anti-friction journal and bearing which shall be simple and durable; and with these ends in view my invention consists in the details of construction and combination of elements hereinafter fully and in detail explained, and then specifically designated by the claims.

In order that those skilled in the art to which my invention appertains may more fully understand its construction and operation, I will proceed to describe the same in detail, referring by letter to the accompanying drawings forming a part of this specification, in which—

Fig. 1 is a side elevation of a truck with my improvement attached; Fig. 2, a plan view of one journal, the truck-frame being removed to show more clearly the relative position of the anti-friction wheels; Fig. 3, a front view of the same, the side bar and boxing being in section, also a portion of the periphery of the wheel being broken away; and Fig. 4 is a view of a pair of the anti-friction wheels.

Similar letters of reference indicate like parts throughout the several views of the drawings.

A is the track-frame, of ordinary construction, and B are the truck-wheels. Side bars, C, (but one of which is shown in the drawings,) may be of any convenient shape, having downwardly-projecting housings D. Also in said side bars are formed journal-boxes e, in which the axles e of the anti-friction wheels E fit and rotate. These wheels are made in pairs, as shown in Fig. 4, so that there will be no unequal strain on them or their bearings. Said wheels E, when journaled in side bars, C, form V-shaped bearings for the journals F of the

truck-wheels B, the said journals F being retained in close contact with wheels E by means of boxings G, adapted to fit between housings D, and held in place by caps I and adjusting-screws K, or in any suitable manner.

By allowing the journals of wheels E no play in the side bars, and keeping the boxings in close contact with the journals F, I prevent the hammering out of said wheels E, which has heretofore been the difficulty with devices for this purpose. Also, by having the wheels E in pairs and journaling them in the center, I economize space, and gain strength and durability.

The side bars, C, are preferably bent or otherwise formed with downwardly-projecting curvatures, so that the spring-seats or the points L on which the lower ends of the car-springs rest shall be slightly lower than the horizontal center of the axle-journal, whereby a "hanging bearing" is provided, and a greater self equalizing, balancing, or self-adjustment is secured between the anti-friction wheels and the axle-journal.

By providing beveled flanges M and O on the axle-journal, and loosely fitting the beveled boxings G between said flanges, the end thrust of the axle is sustained by the boxing without injury or strain to the anti-friction wheels. This construction obviates the objection heretofore existing against anti-friction wheels, where, to the weight of the car, was added the end thrust and longitudinal pressure of the axles against the anti-friction wheels, causing their gripping upon their bearings, and, heretofore, greatly reducing the anti-friction quality of said wheels.

It is obvious that the side bars may be made of any suitable perpendicular width to secure the requisite strength, and that cross-bars, &c., may be secured thereto to form suitable connection with the truck. I leave this part to the mechanical ingenuity of the car-builder, as in my device it is aimed to simply provide a practical anti-friction journal in which former difficulties in the use of anti-friction wheels shall be overcome, and in which a practical combination and arrangement of essential parts shall be secured.

Having thus fully described my invention, what I claim as new and useful is—

1. In journals for cars, the two pairs of anti-friction wheels E, each having single axial bearings between the wheels thereof, and in a bar connecting the pairs, in combination with housings D and boxing G, said boxing receiving the end thrust of the car-axle through shoulder O, substantially as and for the purpose set forth.
2. In journals for cars, the axle F, having shoulders O and M, in combination with boxing G, fitting loosely between said shoulders, and the two pairs of anti-friction wheels E, each pair having a single axial bearing or journal in bar C, said bar passing between the wheels of each pair, respectively, substantially as and for the purpose set forth.

3. In journal-boxes for cars, the side bar, C, connecting the two pairs of anti-friction wheels E by single central bearings in said bar between the wheels of each pair respectively, and said side bar, C, being bent or otherwise formed so as to provide spring-seats L on a line below that of the horizontal center of the car-axle, whereby an equalizing hanging of the bearings is secured, substantially as and for the purpose set forth.

In testimony whereof I affix my signature in presence of two witnesses.

S. STUART WILLIAMSON.
